UNITED STATES PATENT OFFICE.

CARLOS LEFEBVRE, OF VALENCIENNES, FRANCE.

SPLIT BELT-PULLEY.

SPECIFICATION forming part of Letters Patent No. 620,940, dated March 14, 1899.

Application filed September 10, 1898. Serial No. 690,612. (No model.)

To all whom it may concern:

Be it known that I, CARLOS LEFEBVRE, civil engineer, of 1 Place des Nantiers, in the city of Valenciennes, Republic of France, have 5 invented an Improved Split Belt-Pulley, of which the following is a full, clear, and exact description.

My invention relates to a split belt-pulley constructed entirely of sheet metal and possessing the advantages of great lightness and strength, the pulley being made in separable halves united diametrically by means of bolts.

The invention is illustrated by way of example in the accompanying drawings, in 15 which—

Figure 1 represents an elevation, and Fig. 2 a side view, of one-half of the pulley. Fig. 3 is a section on line A B, Fig. 2; and Fig. 4 is a side view of a complete pulley.

20 Each half of the pulley is composed of two semicircular dishes or concave webs *a a*, stamped out of sheet metal and having their circular edges stamped up into flanges *a'*, which abut continuously against the rim *b*, which may be made of suitable form. The rectilinear diametrical or abutting edges *a²* of the webs *a a* have also ears or projections *c* stamped up at a right angle at or near the rim, and also ears or projections *d* stamped 25 up at an angle near the middle of the edge *a²*. The portions so stamped up are perforated to receive the bolts by which the two halves of the pulley are united. Next the rim *b* are disposed angle-irons *e e*, which are connected 30 both to the ears *c c* of the webs *a a* and to the stamped-up flanges *a'* of the latter for the purpose of strengthening the ears. Each half of the boss is formed of a semicylindrical shell *f*, the edges of which are turned 35 outward from the center to form ears *f'* for the purpose of being bolted to the ears *d d* of the webs *a a* to strengthen the same. The two halves of the pulley, constructed as herein-

before described, are united by bolts, as usual in the case of "split" pulleys.

45 The construction of pulley described presents the advantage of being very economical, while at the same time affording great strength both in the rim and web or body of the pulley, which is capable of supporting 50 considerable strains for a considerable period without getting out of shape.

What I claim, and desire to secure by Letters Patent, is—

1. A two-part pulley consisting of semicircular pulley-sections secured together and each comprising two semicircular dished webs *a* stamped up from thin sheet metal with raised peripheral edges or flanges *a'* secured to the rim *b* of the pulley, and provided 55 with integral ears *c c d d* bent away from the web *a* at an angle, whereby the halves of the pulley may be united by bolts passing through the ears.

2. A two-part pulley consisting of semicylindrical pulley-sections secured together to constitute a pulley, each comprising a pair of dished webs *a* formed of sheet metal provided with turned-over circular edges or webs *a'* secured to a rim *b*, integral ears *c* at 60 or near the circular edges turned over at an angle to the web *a*, integral ears *d* at or near the middle of the abutting edge of the web and turned over at an angle to the web and an eared semicylindrical shell *f* adapted 65 to be secured to the bent-over ears *d d* whereby two pulley-sections may be secured together by bolts passing through the ears *c c* and *d d* to constitute a split pulley.

70 The foregoing specification of my improved split belt-pulley signed by me this 27th day of August, 1898.

CARLOS LEFEBVRE.
